UNITED STATES PATENT OFFICE.

AUTHER M. MEDARIS AND RICHARD F. POWELL, OF DENVER, COLORADO.

DESIGN FOR A VAPOR-BATH TUB.

44,378.

Specification for Design.

Patented July 22, 1913.

Application filed August 21, 1911. Serial No. 645,298. Term of patent 7 years.

To all whom it may concern:

Be it known that we, AUTHER M. MEDARIS and RICHARD F. POWELL, citizens of the United States, residing at Denver, in the county of Denver and State of Colorado, have invented a new, original, and ornamental Design for Vapor-Bath Tubs, of which the following is a specification, reference being had to the accompanying drawing, forming part thereof.

The figure is a perspective view of a vapor bath tub, showing our new design.

We claim:

The ornamental design for a vapor bath tub, as shown.

AUTHER M. MEDARIS.
RICHARD F. POWELL.

Witnesses:

S. B. BONTEMS,
M. I. BROWNELL.
